United States Patent Office

Des. 194,334
Patented Jan. 1, 1963

194,334

PACKAGING TRAY

Paul R. Collins, Fairview Park, Ohio, assignor to The Dow Chemical Company, Midland, Mich., a corporation of Delaware

Filed Apr. 13, 1962, Ser. No. 69,707

Term of patent 14 years

(Cl. D58—12.6)

Fig. 1

Fig. 2

Fig. 3

Fig. 4

Fig. 5

FIGURE 1 is a top plan view of a packaging tray, showing my new design;

FIGURE 2 is a side elevational view thereof;

FIGURE 3 is an end elevational view thereof;

FIGURE 4 is an enlarged fragmentary cross-sectional view taken on line 4—4 of FIG. 1; and

FIGURE 5 is an enlarged fragmentary cross-sectional view taken on line 5—5 of FIG. 1.

The side and end views not shown are the same as the side and end views illustrated.

I claim:

The ornamental design for a packaging tray, substantially as shown and described.
